UNITED STATES PATENT OFFICE.

JOSEPH J. NORVELLE, OF PITTSFIELD, MASSACHUSETTS.

DESIGN FOR A DISPLAY CASE OR SIMILAR ARTICLE.

Application filed November 3, 1927. Serial No. 23,997. Term of patent 14 years.

To all whom it may concern:

Be it known that I, JOSEPH J. NORVELLE, a citizen of the United States, residing at Pittsfield, in the county of Berkshire and State of Massachusetts, have invented a new, original, and ornamental Design for a Display Case or Similar Article, of which the following is a specification, reference being had to the accompanying drawing, forming a part thereof.

The figure is a front perspective elevation view of a display case embodying my design.

I claim:

The ornamental design for a display case or similar article as shown.

JOSEPH J. NORVELLE.
